UNITED STATES PATENT OFFICE.

GEORGE A. FREDERICKS, OF NEW YORK, N. Y.

SUBMARINE BOAT.

1,188,436.

Specification of Letters Patent. Patented June 27, 1916.

Application filed February 2, 1915. Serial No. 5,769.

To all whom it may concern:

Be it known that I, GEORGE A. FREDERICKS, a citizen of the United States, residing at New York, in the county of New York, State of New York, have invented certain new and useful Improvements in Submarine Boats; and I do hereby declare the following to be a full, clear, and exact description of the invention, such as will enable others skilled in the art to which it appertains to make and use the same.

This invention relates to submarine boats.

The object of the invention resides in the provision of a submarine boat embodying an improved construction whereby a diver may enter and leave the boat when same is beneath the surface of the water.

With the above and other objects in view the invention consists in the details of construction and in the arrangement and combination of parts to be hereinafter more fully described and particularly pointed out in the appended claim.

In describing the invention in detail reference will be had to the accompanying drawings wherein like characters of reference denote corresponding parts in the several views, and in which—

Figure 1 is a transverse section through a fragment of a submarine boat embodying the invention; Fig. 2, a section on the line 2—2 of Fig. 1; Fig. 3, a section on the line 3—3 of Fig. 1; Fig. 4, a longitudinal section through a fragment of the submarine boat and disclosing certain features essential to the invention; Fig. 5 a view in elevation of the outer side of the inner door of the diver's room; Fig. 6, a section on the line 6—6 of Fig. 4; Fig. 7, a section on the line 7—7 of Fig. 2, and Fig. 8, a section on the line 8—8 of Fig. 7.

Referring to the drawings 10 indicates the body of a submarine boat in one side of which is built a diver's room indicated generally at A and including a front wall 11, a rear wall 12, side walls 13, a top wall 14, and a bottom wall 15. The rear wall 12 is provided with an opening 16 adapted to be closed by a door 17, the latter being provided with a gasket 18 to render same water tight when in closed position. The wall 12 is provided adjacent the opening 16 with a threaded recess 19 in which is adapted to be engaged a locking screw 20 rotatably mounted on the door 17 adjacent the free edge of the latter. This locking screw 20 is pro-

vided with a circumscribing flange 21 adapted to bear against the door 17 as the screw 20 advances into the recess 19 and thus force the door into closed position and compress the gasket 18 to produce a water tight joint. The wall 11 is likewise provided with an opening 22 adapted to be closed by a door 23. This door 23 is provided with an arm 24 the free end of which is fixed to a shaft 25 rotatably mounted in bearings 26, said shaft being disposed above the room A. Rotatably mounted adjacent the shaft 25 and parallel thereto is a shaft 27 adapted to be rotated through the medium of any suitable source of power located within the boat. It will be noted that the wall of the boat is recessed at 28 to receive the shaft 25 and expose a portion of the shaft 27. Fixed upon the shaft 25 is a gear 29 which meshes with a gear 30 fixed upon the shaft 27 and whereby rotation of the latter will impart opening and closing movement to the door 23 as will be obvious. Mounted on the inner side of the door 23 is a bracket 31 in which is rotatably mounted a locking screw 32. This screw is threaded centrally through a locking bar 33 adapted to travel in guides 34 mounted upon the door 23. Mounted upon the wall 11 adjacent each side of the opening 22 is a keeper 35 adapted to receive the ends of the bar 33 when the latter is disposed in locking position. In order to lock the door 23 the various parts are disposed in the position shown in Fig. 2 and the screw 32 rotated so that same will advance through the bar 33. As the latter is held against movement by the keepers 35 it will be apparent that the door 23 will be forced to closed position with sufficient power to effect the necessary water tight joint. When the doors 17 and 23 are closed water may be supplied to and removed from the room A through the medium of a pipe 36 connected through the bottom 15 and further connected with a pump 37. Under the same conditions air is supplied to and removed from the room A through the medium of a pipe 38 which may be connected selectively to a pump for supplying air or to a pump for exhausting air. Air connections for the diver are carried into the room A through the wall 13 and are indicated at 39, while a telephone connection 40 and an electric light connection 41 are carried into the room A through the wall 13. A suitable electric light 42 is mounted upon the top wall 14 and is supplied through an electric

conductor 43 leading from the dynamo of the boat.

Assuming the parts to be in their normal position the door 23 will be locked closed and the door 17 unlocked and free to swing. The diver can then enter the room A from the interior of the boat proper through the opening 16. After he has entered the room the door 17 is swung closed and locked. The 10 diver then attaches the air connections 39, telephone connections 40 and electric light connections 41 to his paraphernalia. Water is then pumped into the room A and the air simultaneously removed. The diver then 15 unlocks the door 23 and signals for same to be opened through the medium of the mechanical means heretofore described. With this condition existing the diver can enter the sea and return to the room A at his 20 pleasure. When the diver desires to return to the boat the operation just described is reversed.

What is claimed is:—

In a structure for affording ingress and egress to and from submarine boats beneath the water line, the combination with the hull

of a submarine boat, of a room constructed within the boat and having its outer wall in common with the hull and provided with an opening, said hull being offset inwardly 30 above the room to provide a space constantly in communication with the sea, an operating shaft rotatably mounted on the hull and extending through said space, a pinion on said operating shaft disposed within the space, a second shaft rotatably mounted on the hull parallel to the first shaft, a pinion on the shaft meshing with the pinion on the first shaft, an arm fixed on the second shaft, a door carried by said arm and movable to a 35 position to close the opening in the wall by rotation of the first shaft, a locking device on the interior of said door, a second door included in one of the inner walls of the room, and a locking device on the inner side of the 40 second door.

In testimony whereof, I affix my signature, in the presence of two witnesses.

GEORGE A. FREDERICKS.
